UNITED STATES PATENT OFFICE.

HORACE N. RANDALL, OF MINNEAPOLIS, MINNESOTA.

CORN-PLANTER.

1,114,385.

Specification of Letters Patent. Patented Oct. 20, 1914.

Application filed April 11, 1913. Serial No. 760,358.

To all whom it may concern:

Be it known that I, HORACE N. RANDALL, a citizen of the United States, residing at Minneapolis, in the county of Hennepin and 5 State of Minnesota, have invented certain new and useful Improvements in Corn-Planters, of which the following is a specification.

My invention relates to corn planters and 10 particularly to that type of planters such as disclosed in my prior Patents Numbers 913,234 and 913,235, granted February 23, 1909, in which a marker device makes a series of check marks at one side of the 15 machine, and an indicator on the machine works synchronously with the checking device and the planter mechanism indicating whether or not the marker and the planter mechanism are operating to keep the cross 20 rows in true alinement.

It is the primary object of my present invention to provide simple and easily operated means to adjust the indicator and marker mechanism so as to bring the operation 25 of the same into true alinement with the cross rows when from any reason such alinement has been lost.

It is also an object of my invention to provide improved means of operating the indicator device.

The full objects and advantages of my invention will appear in connection with the detailed description thereof and are particularly pointed out in the claims.

35 In the drawings, illustrating the application of my invention in one form,—Figure 1 is a plan view of a machine embodying my improvements. Fig. 2 is a sectional elevation with some parts omitted. Fig. 3 is 40 a small diagrammatic plan view showing the relation of the check marks. Figs. 4 and 5 are sectional views of the foot-operative device for throwing the machine into and out of gear, showing the parts in two different 45 positions. Fig. 6 is a side view on a large scale of a portion of the drive shaft showing the disk for rotating the same. Fig. 7 is a sectional end view of the parts shown in Fig. 6.

50 Side frame pieces 10 are provided to which are secured brackets 11 formed with boxes 12 in which is journaled a transverse shaft 13. The said shaft 13 extends outside of the frame piece 10 and is provided with 55 spindles 14 upon which are journaled wheels 15. The wheels 15 are adapted to rotate

freely upon the spindles 14 and are provided with hubs 16 having inner clutch faces adapted to be engaged by clutch members 17 slidably mounted upon shaft 13 and normally pressed into active engagement with hub faces 16 by means of spiral springs 18 surrounding shaft 13. The clutch members 17 are formed on collars 19 which are splined to the shaft 13, said collars being 60 provided with grooves 20 which receive the ends 21 of clutch fork arms 22 and 23, respectively. The arms 23 are pivotally secured to a post 24 fast on side frame member 10 and have angularly disposed arm portions 25 which extend inwardly so that the ends thereof are adjacent one another at the central part of the machine. The ends of members 25 are pivotally connected by links 26 with short arms 27 pivotally connected 70 at 28 to the stand 29 on the frame 30 extending across the machine. The arms 27 are bent at an angle beyond the pivot point to form a foot lever 31. Normally the foot lever will be in the position shown in Fig. 80 4, in which case the springs 18 will be operative to hold the clutch members 17 in engagement with the clutch faces on hubs 16, and shaft 13 will rotate with wheels 15. If at any time it is desired to have said wheels 85 15 rotate independently of shaft 13, or, stated in another way, if it is desired to rotate shaft 13 independently of wheels 15, by means of the foot of the operator, the foot lever 31 may be drawn into the position 90 shown in Fig. 5 when clutch members 17 will be withdrawn from engagement with hub faces 16, and wheels 15 and shaft 13 will be released for relative rotation.

95 Seed delivering hoppers 32 are mounted upon the ends of a crossbar 33 in line with wheels 15, and the shaft 34 for operating said seeding mechanism is driven by means of a sprocket chain 35 from a sprocket wheel 36 on the shaft 13. As best shown in Fig. 3, 100 100 a marker shaft 36' is secured by universal joint to one end of shaft 13 and rotates with said shaft, said marker shaft comprising check row marking devices 37 such as are shown and described in my said prior Patent 105 Number 913,235. A lever 38 having an indicator finger 39 is pivoted to the frame member 40. This indicator lever is normally held so that the finger 39 is out of contact with the ground by means of a bolt 41 on a 110 floating arm 42 which arm is pivotally connected at 43 with a rocking lever 44 and at

bolt 41 is pivotally connected with a pair of links 45 which in turn are fast on shaft 46 journaled in the lower portions of hangers 47 depending from crossbar 33. The bolt 41 does not directly engage the arm 38 but engages a bearing piece 48 which is secured to arm 38, said bearing piece having a lower face sufficiently extended so that it will at all times ride upon bolt 41, a notch 49 being cut in said bearing piece to allow the same to clear the shaft 46. The links 45 and the parts connected therewith are held in normal position by means of a pair of curved lever springs 50 secured at their upper ends to crossbar 33 and pivotally attached at their lower ends to bolt 41. A bolt 51 is pivotally secured at 52 to lever 38 and extends through an aperture in a stand 53 fast on crossbar 33. A spiral spring 54 surrounding bolt 51 and extending between stand 53 and lever 38 holds the bearing piece 48 in continuous contact with bolt 41. The rocking lever 44 is pivoted at 55 below the crossbar 30 and has the extended end 56 thereof provided with an adjustable trip piece 57 in the path of rollers 58 on a series of arms 59 secured to shaft 13, said arms 59 bearing a fixed relation to the marker members 37 on the shaft 36.

From the above it will be seen that rotation of shaft 13 operates the marker mechanism, the seeder mechanism and the indicator synchronously. At the moment when the seeder mechanism is operated to deposit seed at the proper point in the ground the marker member 37 is making a mark at one side and the trip 57 will have been engaged by a roller 58 causing the rocking lever 44 to lift floating member 42 and with it indicator lever 38 compressing leaf springs 50 and spiral spring 54; and just as a mark 60 is made by one of the marker mechanisms the trip piece 57 will be released and the springs 50 will swing links or arms 45 downwardly simultaneously rocking shaft 46 and with it the seeding arms 61 and the indicator lever 38 and indicator finger 39. It will be apparent therefore that the indicator finger 39 operates in the same transverse plane as the seed-dropper mechanism. If the finger 39 enters the check mark 60 at the center of the rows over which the machine is operating, the machine is working to plant the cross rows in correct alignment. The finger 39 is carried beyond its normal position by inertia so that its end is depressed below the surface of the ground and normally contacts with the same whether parts 60 are in transverse alignment or not. If, however, either from slippage of the wheels in passing over uneven portions of the ground, when turning around, or from any other causes, the indicating finger 39 comes out of position with respect to a mark 60, it is necessary to adjust shaft 13 and the

parts carried thereby and connected therewith in reference to wheels 15. To accomplish this the wheels are first unclutched by means of the foot lever 31 and connected parts above described, and then by means of a lever 62 pivotally mounted on one of the bearing boxes 12 and which is capable of being caused to engage in notches 63 in a disk 64 fast on shaft 13, the said shaft may be turned the desired distance to make the proper adjustment. As shown in Fig. 7, the lever 62 is hinged for pivotal movement in the plane of the shaft 13 at 65, being held normally in an upright position by means of a spring marker 66 secured to lever 62 which takes over a segment ring 67 secured to bracket 11. It is to be noted that the notches 63 are of such size relative to the width of lever 62 that the body or shaft of lever 62 may engage in said notches whenever said lever is drawn outwardly against the force of spring 66. The segment ring 67 is preferably graduated on its face and sides, as indicated in Fig. 6, the graduations indicating the number of inches which the turn of the shaft 13 will effect in the matter of change of position of the parts carried by said shaft relative to wheels 15. In operation this lever will, when the shaft 13 has been unclutched from the wheels, be engaged in a notch 63 either at one end or the other of the said scale, which is preferably limited by means of pieces 68 which extend into the path of the lever 62. By means of the lever the shaft 13 is then turned relative to wheels 15 a sufficient distance to compensate for the difference in alignment of the parts, as indicated by the finger 39, with reference to marks 60.

It will be apparent that an operator, observing at any time in connection with the operation of the machine that the indicator finger 39 is either at the front or the rear of the center of a mark 60 and noting the distance of said indicator from said center, can, with no more loss of time than is necessary to stop the machine for a moment, press down on foot lever 31 and operate hand lever 62 and make the necessary adjustment for keeping the parts in true alignment.

The advantages of this conveniently operated apparatus are very apparent. It makes a machine which with the most ordinary care can be caused to do absolutely accurate work in cross checking. The movement of the shaft 13 relative to wheels 15 simultaneously moves the marker mechanism 37, the arms 59 which operate the indicator finger 39 and planter shaft 46 and the sprocket chain 35 and said depositing shaft 34, so that every part necessary for effecting correction of alignment is moved synchronously and in operatively related manner.

I claim:

1. A corn planter comprising a shaft, 130

traction wheels loose on said shaft and having clutch faces on the hubs thereof, clutch members splined to the shaft, springs surrounding the shaft and normally forcing said clutch members into engagement with the clutch faces on the hubs, a foot lever and connections to said clutch members whereby the same may be simultaneously moved against the force of the springs into 10 inoperative position, a hand lever pivoted upon a fixed member, means fast on the shaft adapted to be engaged by the hand lever for the purpose of rotating said shaft independently of the wheels when said 15 clutches are held inoperative, and cross-row mechanism, seed-dropper mechanism and indicator mechanism actuated from said shaft.

2. A corn planter comprising a shaft, traction wheels loose on said shaft and having clutch faces on the hubs thereof, clutch members splined to the shaft, springs surrounding the shaft and normally forcing said clutch members into engagement with the clutch faces on the hubs, a foot lever and 20 connections to said clutch members whereby the same may be simultaneously moved against the force of the springs into inoperative position, a collar rotatably mounted upon a fixed member surrounding said shaft, a hand lever pivoted to said collar for oscillation in the plane of the shaft, a ring carried by said fixed member, a disk fast on the shaft having notches facing the lever of a size to receive the same, a spring on the lever 25

30

engaging said disk and normally holding 35 said lever out of said notches, and cross-row marker mechanism, seed-dropper mechanism and an indicator mechanism actuated from said shaft.

3. A corn planter comprising a shaft, 40 traction wheels on said shaft for operating the same at will, cross row marker mechanism connected with said shaft, a spring-supported oscillating member, an indicator lever resting upon said member, an actuating lever for operating said indicator mechanism, and a series of members on the shaft for successively operating the actuating member.

4. A corn planter comprising a shaft, 50 traction wheels on said shaft for operating the same at will, cross row marker mechanism, seed dropper mechanism, an indicator finger operative in the plane of the seed dropper mechanism, spring-controlled means 55 normally holding said finger out of engagement with the ground, an oscillating lever connected with said spring controlled means, and a series of members on the shaft for successively engaging and oscillating said 60 lever.

In testimony whereof I affix my signature in presence of two witnesses.

HORACE N. RANDALL.
